TABLE

Frank W. Leidig, 280 Orange St., Galion, Ohio 44833

Filed Nov. 20, 1969, Ser. No. 20,187

Term of patent 14 years

Int. Cl. D6—01

U.S. Cl. D33—14

FIG. 1

FIG. 3

FIG. 1 is a view in side elevation of a table showing my new design;

FIG. 2 is a view in top plan of the structure with the top and its depending skirt removed taken substantially on the line 2—2; and

FIG. 3 is a view in side elevation taken at an angle of 45° from the view in FIG. 1.

The top surface of the table is plain and unornamented. I claim:

The ornamental design for a table, as shown and described.
